ATTORNEY.

UNITED STATES PATENT OFFICE

CHARLES S. CHRISMAN, OF WEST CHESTER, PENNSYLVANIA, ASSIGNOR TO THE U. G. I. CONTRACTING COMPANY, OF PHILADELPHIA, PENNSYLVANIA, A CORPORATION OF DELAWARE

WATER-GAS APPARATUS

Application filed April 18, 1925. Serial No. 24,084.

The principal object of the present invention is to provide for easily and safely reversing the flow of steam and gas through a water gas apparatus by valve means external 5 to the flow or path of the products of combustion. Another object of the invention is to provide that said valve means shall automatically control in its operation the steam supply to the water gas apparatus. Another 10 object of the invention is to provide for the employment of reversing valve means which shall be comparatively inexpensive in respect both to first cost and to maintenance in comparison with what are commonly 15 called and are well understood as hot valves which are dispensed with. Another object of the invention is to take advantage of the difference in pressure due to the fuel bed in order to insure that the reversing valve means 20 when positioned shall be forced to seat.

Other objects will appear from the following description but it may be said that, generally stated, the invention comprises water gas apparatus including in combination a set 25 of vessels having operatively valveless inter-communication and including a generator and its fuel bed provisions, a wash box, a valve casing arranged outside of said vessels and having two ported admission chambers 30 respectively communicating with the ends of the set of vessels and having an outlet chamber communicating with the wash box and with said admission chambers, a reciprocating shaft carrying a pair of disks spaced 35 on the pressure side of said ports and each when closed held in closed position by the pressure due to the difference in pressure at the ends of the set, and steam cylinders and pistons for shifting the shaft against said 40 pressure and each having valve elements and connections for reversing the steam supply to the set. The invention also comprises the improvements to be presently described and finally claimed.

45 In the description reference will be made to the accompanying drawings forming part hereof and in which

Figure 1 is an elevational view illustrating a set of blue water gas apparatus vessels to 50 which the invention is shown in application.

Fig. 2 is a sectional plan view drawn to an enlarged scale, taken generally on the line 2—2 of Figure 1, and turned through 90° from the position shown in Fig. 1, and

Fig. 3 is a sectional elevational view taken 55 on the line 3—3 of Fig. 2.

1, 2 and 3 are the vessels of blue water gas apparatus chosen from among other water gas apparatus for the sake of explanation of the invention. Of these 1 is a water gas 60 generator having fuel bed provisions 4, and 2 is an igniter. 3 is a steam generator or steam boiler. The gas apparatus 1 and 2 intercommunicates by means of the connection 5 which is operatively valveless, and the igniter 2 65 and boiler 3 are in communication by means of the connection 6 which is also operatively valveless. 7 is a wash box from which the gas is led away for storage or use. 8 is an air connection by which air is introduced 70 under the grate 4 and through the fuel bed thereon with the production of blast gas which passing by 5 may receive additional air by connection 9 and which is ignited in the vessel 2 from which it passes by 6 downward 75 through the boiler and thence the products of combustion pass by the stack connection 10 fitted with a valve generally indicated at 11. The step described is commonly called the 80 blow. The apparatus shown is adapted for up and down runs meaning that steam is passed either upward or downward through the fuel bed, the resultant water gas being led off at the top or bottom of the generator. The valve 11 is closed during each run and 85 at an up run the path of the gas is from the generator 1, by 5 through a vessel or vessels of which 2 is representative, by 6 through the boiler, when present, and by the end connection 12 of the set, and at a down run the path 90 of the water gas is from the generator 1 by end connection 13. For the down run 14 is a steam connection and for the up run end connection 13 serves as a steam connection. 95 15 is a valve casing arranged outside of the vessels of the set and it has two admission chambers 16 and 17 respectively communicating with the end connections 13 and 12 of the set of vessels. These chambers are provided with ports 18 and 19 leading to the out-

let chamber 20 that communicates with the wash box 7. 21 is an endwise reciprocatable shaft and it carries a pair of disks 22 and 23 spaced on the pressure side of the ports 18 and 19 and each, when closed, held in a closed position by the pressure due to the difference in pressure at the ends of the set which difference in pressure arises by reason of the presence of the fuel bed at 4. 24 is a man-hole cover. There are steam cylinders 25 and 26 and pistons 27 and 28 for shifting the shaft 21. 29 is a steam inlet connection to a fourway cock 30 from which lead a pipe 31 to the end of the cylinder 26, and a pipe 32 to the end of the cylinder 25, and an exhaust 33 which may well be contracted or restricted so as to delay exhaust from the cylinders and thus prevent too quick movements of the shaft 21 and valve disks 22 and 23. 20 The piston 27 cooperates as a valve element to cover and uncover a port 34 leading to steam pipe 14. The piston 28 cooperates with the port 35 as a valve element to cover and uncover the port 35 to admit and exclude steam to the chamber 16 which communicates with the connection 13.

With the parts in the positions shown and with the valve 11 closed, steam is passed from 29, by 32, 25, 14, 6, 2 and 5 to the top of the 30 water gas generator, and water gas is passed from the bottom of the generator by 13, 16, 18 and 20 to the wash box. The pressure on top of the fuel bed is greater than the pressure under it and the greater pressure is acting on the disk valve 23 to hold it to its seat. When the fourway valve 30 is in its righthand position steam passes by 29, 31, to cylinder 26, which steam moves piston 28 and shaft 21 toward the right with proper movement due 40 to the restricted exhaust from the cylinder 25, by 32 and 33, thus the disk 22 is seated and the disk 23 unseated and steam passing through the cylinder 26 and port 35 reaches the chamber 16, which communicates by 13 with the base of the generator 1. The greater pressure which exists beneath the fuel bed acts to hold the disk 22 to its seat. The port 19 is uncovered and gas passes by 5, 2, 3, 12, 17, 19 and 20 to the wash box. By a repetition 45 of the described operations the reversing valve is effective to produce up and down steam runs in response, in the present instance, to the manual setting of the valve 30. There is an advantage in passing steam 50 through the connection 13 in that it insures the removal of gas from the lower part of the water gas generator where it might be exploded upon the admission of the air for the succeeding air blasting step. In connection 55 with the described reversing valve it is an advantage that it controls not only the direction of gas flow but also the appropriate location for introducing steam into the generator so that erroneous connections may not 60 be made. Another advantage of the de-

scribed reversing valve is that steam is not admitted to either end of the set until communication at the end of the set at which steam is admitted with the wash box outlet 20, which leads to a gas holder, is closed.

It will be obvious to those skilled in the art to which the invention relates that modifications may be made in details of construction and arrangement and in matters of mere form without departing from the spirit of the invention which is not limited to such things or otherwise than the prior art and the appended claims may require.

I claim:

1. A water gas apparatus including in combination; a water gas generator adapted to contain a fuel bed, an igniter, a steam boiler, pipe connections between the generator and boiler, valve mechanism including a steam reversing valve controlling the flow of steam to the generator, a water gas flow valve controlling the flow of water gas from the generator, the flow valve comprising a reciprocating shaft having pistons and disks attached thereto, said pistons being controlled by the steam reversing valve, and a steam connection from the steam reversing valve to the igniter.

2. A water gas apparatus including in combination; a water gas generator adapted to contain a fuel bed, a valve casing, a conduit leading from the top of said generator, to said valve casing, a conduit leading from the bottom of said generator to said valve casing, said valve casing containing chambers connected to said conduits and an outlet chamber separated from said chambers by partitions, a rod mounted in said casing, disks and pistons mounted on said rod, cylinders in which said pistons reciprocate, a steam supply inlet, a valve connected to said inlet and operable to connect either of said cylinders with said steam supply and the other of said cylinders with an exhaust, said disks cooperating with openings in said partitions so as to connect one of said conduits with said outlet chamber and to close connection between the other conduit and said outlet chamber, a port adapted to be closed by one piston between one cylinder and the chamber connected to the conduit connected to the lower end of said generator, a port adapted to be closed by the other piston leading from the other cylinder, a connection from said last port to the conduit connected to the upper part of the generator, and a wash box connected to said outlet chamber.
